CLAIM

The ornamental design for a mouse trap, as shown and described.

DESCRIPTION

FIG. 1 is a front elevational view of a mouse trap showing my new design;
FIG. 2 is a rear elevational view thereof; and
FIG. 3 is a left side view thereof;
FIG. 4 is a right side view thereof;
FIG. 5 is a top plan view thereof;
FIG. 6 is a bottom plan view thereof;
FIG. 7 is a perspective view of a mouse trap showing my new design;
FIG. 8 is another perspective view thereof; and,
FIG. 9 is a partial enlarged view of FIG. 6.
The broken lines in the figures are for the purposes of illustrating portions of the mouse trap, which form no part of the claimed design.
